UNITED STATES PATENT OFFICE.

PETER L. LAZARUS, OF WICHITA, KANSAS.

EGG-HOLDER.

1,188,662.

Specification of Letters Patent. Patented June 27, 1916.

Application filed March 4, 1915. Serial No. 12,039.

To all whom it may concern:

Be it known that I, PETER L. LAZARUS, a citizen of the United States, residing at Wichita, in the county of Sedgwick and State of Kansas, have invented a new and useful Egg-Holder, of which the following is a specification.

This invention relates to holders for eggs and the like, especially designed for use for 10 protecting eggs from injury while being transported, one of the objects of the invention being to provide a rack of simple construction adapted to be engaged by opposite portions of a wrapper surrounding the egg 15 or other article to be transported, whereby the said article is held out of contact with any portion of the container in which it is located, thus preventing injury.

A further object is to provide a holder of 20 this character which is cheap to manufacture, is light and durable, and which is especially useful in connection with parcel post packages, express packages and the like, although it is to be understood that the same 25 can likewise be employed in large crates and like containers.

With the foregoing and other objects in view which will appear as the description proceeds, the invention resides in the combination and arrangement of parts and in the 30 details of construction hereinafter described and claimed, it being understood that changes in the precise embodiment of the invention herein disclosed, can be made 35 within the scope of what is claimed, without departing from the spirit of the invention.

In the accompanying drawings the preferred form of the invention has been shown.

40 In said drawings, Figure 1 is a perspective view of a shipping unit embodying the present improvements. Fig. 2 is a perspective view of the bracket portion of the holder. Fig. 3 is a vertical section through 45 the bracket, an egg and its wrapper being shown in position.

Referring to the figures by characters of reference 1 designates a frame or bracket made out of light wire of sufficient stiffness, 50 the same being preferably substantially rectangular and provided, at its ends, with loops or depressions 2 located directly opposite each other and at the centers of said ends. These loops are extended toward each 55 other.

A frame or bracket such as described is adapted to be used in connection with a housing 3 which can be cylindrical as shown in Fig. 1 or of any other desired contour, the frictional engagement of the side portions of the frame or bracket 1 with the wall of the container being sufficient to prevent the said frame or bracket from slipping out of position accidentally.

When it is desired to mount an egg with- 60 in the container 3, said egg is placed in a wrapper of tissue paper or the like, the end portions of the wrapper being twisted together as at 4. The wrapped egg is then placed inside of the frame or bracket 1 after 65 which the twisted end portions 4 are forced into the loops or depressions 2 with the result that the egg or other article is held suspended in its wrapper and within the frame. The said frame or bracket 1 is then inserted 70 into the container 3 which will be snugly engaged thereby and, obviously, the supported article will thus be held out of contact with all portions of the container 3 so that even though the container should be 75 subjected to rough usage, the chance of injury to the supported articles is remote.

A number of units such as shown in Fig. 1 may be assembled in a box or crate used 80 for shipping purposes.

85 Although the structure is especially designed for use as an egg holder, various other articles which are easily injured while being transported, could be placed advantageously in a holder such as described.

90 What is claimed is:—

The combination with a container, of a frame formed of wire and detachably mounted within the container, the wall of the container constituting means for centering the frame within the container, said frame having loops extending toward each other from the centers of the ends of the frame, said loops constituting clips for receiving and holding the twisted ends of an 95 article holding wrapper arranged within the frame.

100 In testimony that I claim the foregoing as my own, I have hereto affixed my signature in the presence of two witnesses.

PETER L. LAZARUS.

Witnesses:

I. LESEM,
ELLA HADLEY.
